UNITED STATES PATENT OFFICE

161,065

FISH LURE CARRIER

Lester B. Stratman, Santa Monica, and
Frank W. Newton, Los Angeles, Calif.

Application October 1, 1949, Serial No. 5,254

Term of patent 7 years

(Cl. D31—4)

To all whom it may concern:

Be it known that we, Lester B. Stratman and Frank W. Newton, citizens of the United States of America and residents, respectively, of Santa Monica and Los Angeles, in Los Angeles County, State of California, have invented a new, original, and ornamental Design for a Fish Lure Carrier, of which the following is a specification, reference being had to the accompanying sheet of drawing, forming part thereof. In the drawing:

Figure 1 is a perspective view of a fish lure carrier, showing our new design;

Figure 2 is an end view thereof; and

Figure 3 is a rear view thereof.

We claim:

The ornamental design for a fish lure carrier, substantially as shown.

LESTER B. STRATMAN.
FRANK W. NEWTON.
